CHARLES A. THOMAS AND CARROLL A. HOCHWALT, OF DAYTON, OHIO, ASSIGNEES TO
THOMAS & HOCHWALT LABORATORIES, INC., OF DAYTON, OHIO, A CORPORATION OF
OHIO

COMPOSITION FOR REMOVING CARBON DEPOSITS

No Drawing.

Application filed October 3, 1929. Serial No. 397,144.

This invention relates to compounds for removing carbon deposits such as are formed in internal combustion engine cylinders.

One of the principal objects of this invention is to provide a superior composition which is unusually effective in removing such deposits.

Another object of the invention is to provide such a composition for removing such carbon deposits which is quite cheap, has a relatively high boiling point, and has no objectionable deleterious effects upon metal parts with which it comes in contact, such as the cylinder of an internal combustion engine.

Still another object of the invention is to provide a composition of this character which serves to maintain the loosened carbon deposits within an engine cylinder in a condition such as to prevent rattling of the loosened deposits or other objectionable results upon restarting of the engine.

Other objects and advantages of the invention will be apparent from the following description and appended claims.

Carbon deposits such as are formed in internal combustion engines are found to consist primarily of the following ingredients: (1) road dust which consists principally of silica; (2) lubricating oil resulting from seepage past the piston rings; (3) graphitic carbon which results primarily from cracking of the gasoline and lubricating oil; and (4) oxidized lubricating oil which results from the oxidation of the ordinary lubricating oil which has seeped past the piston rings, this oil being oxidized at the high temperatures present in the cylinder and in the presence of oxygen of the fuel mixture. The oxidized lubricating oil, which comprises a number of complex and undetermined compounds of carbon, oxygen and hydrogen, forms a resistant binder or cement which binds the road dust and graphitic carbon together to hold them tightly onto the cylinder head, the piston top, and other portions confining the combustion space.

Various solvents, such as alcohol and benzol, which for purposes of description are hereinafter termed "varnish removing" sol-

vents, have been used in an attempt to dissolve out such deposits. These solvents are found to have a solvent action upon the ordinary unoxidized lubricating oil, but the oxidized lubricating oil or binder is very 55 resistant and is only dissolved to an ineffectual degree by such solvents.

We have discovered that certain compounds, namely the halogenated aromatic hydrocarbons, have a superior solvent action 60 upon this binder. For example, we have discovered that the chlorinated naphthalenes, $C_{10}H_{8-x}Cl_x$ in which x represents the number of substituted chlorine atoms, are very effective 65 carbon removers. Thus monochlor-naphthalene, either alpha or beta, $C_{10}H_7Cl$, which is an aromatic organic compound containing two benzene rings having one substituted halogen, is an excellent compound of this character. We have discovered that 70 other aromatic hydrocarbons containing at least one benzene ring having a substituted halogen, such as the chlor-benzene compounds $C_6H_{6-x}Cl_x$, and the brome-benzene compounds, $C_6H_{6-x}Br_x$, are excellent carbon 75 removers, such for example as phenyl chloride C_6H_5Cl and the dichlorbenzenes $C_6H_4Cl_2$.

Other compounds in this classification containing at least one benzene ring and having a substituted halogen, in which some of the 80 other hydrogen atoms of the benzene nucleus have been substituted by radicals, such as a methyl radical, or phenyl radical are also effective carbon removers. For example, the halogenated toluenes such as monochlor-toluene $C_6H_5CH_3Cl$, the halogenated xylenes such as monochlor-xylene $C_6H_5(CH_3)_2Cl$, and the halogenated dibenzenes such as chlordiphenyl $(C_6H_5)_2Cl_2$, satisfy the requirements of carbon removing compounds 85 90 in accordance with this invention.

Other halogenated hydrocarbons containing at least one benzene ring, which have a side chain including a substituted halogen in the side chain, we have discovered to be effective carbon removing compounds. For example, benzal chloride $C_6H_5CHCl_2$, and benzyl chloride $C_6H_5CH_2Cl$, in which the chlorine atom is, or atoms are, connected to the side chain, are good carbon removers. 95 100

Certain of the halogenated hydrocarbons mentioned, such as some of the chlorinated naphthalenes, and dichlorbenzenes, are solids at ordinary temperatures. In order to place these compounds in a suitable form for use and to make their application easy and more effective, these compounds are preferably dissolved in suitable varnish removing solvents, such as various alcohols, ether, acetone, ethyl acetate, benzene, and the like. A very satisfactory varnish removing solvent for this purpose is a mixture of ethyl alcohol and benzol (commercial benzene). We find it preferable to use absolute alcohol to insure the solubility of the desired amount of certain of the halogenated hydrocarbons. Thus considerably higher percentages of the chlorinated naphthalenes can be dissolved in absolute alcohol than in 95% alcohol, for example. The proportions of the various constituents may be varied within considerable limits, but it is found that more effective results are secured with a substantial portion of each of the three constituents, namely, the ethyl alcohol, benzene and the halogenated hydrocarbon, present.

We have discovered that more effective results are obtained when chlorinated hydrocarbons having a high boiling point are used, this preventing excessive evaporation and escape of the carbon removing composition when introduced into a heated engine cylinder. The chlorinated naphthalenes, such as monochlor-naphthalene which has a boiling point of 264° C., provide excellent compounds for this purpose. It is found preferable to have rather large percentages of the halogenated hydrocarbon, such as the chlorinated naphthalene, present in the composition in order to raise the boiling point of the composition as well as to increase the solvent action upon the resistant binder. The varnish removing solvents function not only as a carrier or solvent for the halogenated hydrocarbons, but also serve to attack the unoxidized lubricating oil and the like of the carbonaceous resinous deposit.

A high boiling point compound such as a chlorinated naphthalene of the character mentioned above not only functions as a superior solvent for the oxidized binder of the deposits, but also serves to maintain the loosened carbon deposits within an engine cylinder in a moist or mushy condition. This is quite important, for where the carbon remover functions in a superior manner as is the case with the present composition to loosen large quantities of deposits within an engine cylinder, these loosened particles may result in objectionable operating conditions upon restarting of the engine if they are not maintained moist or in a mushy condition. This is particularly true in the case of high compression engines having small clearances between portions of the piston and head or

between the valves and the head. In such case, if the carbon remover is of a character which permits the loosened deposits to dry out during standing and before the restarting of the engine, then these dry loosened particles may jam between the piston or valves and the head to cause objectionable knocking or even fracture of the engine parts when the motor is started. The present composition is effective to loosen the deposits as well as to insure against such objectionable operating conditions upon restarting of the engine, for the moist or mushy deposit is free to flow within the clearance space which prevents objectionable jamming between the piston or valve and the head.

As an example of a superior composition prepared in accordance with this invention, the following is mentioned:

	Per cent by volume	85
Monochlor-naphthalene	50	
Absolute denatured ethyl alcohol	25	
Benzol (commercial benzene)	25	

A chlorinated benzene such phenyl chloride C_6H_5Cl , may be used in conjunction with the monochlor-naphthalene in the above example with good results. When phenyl chloride is used, ordinary denatured ethyl alcohol is satisfactory, and absolute alcohol need not be used to insure solubility of the desired amount of the halogenated hydrocarbon.

The chlorinated naphthalenes, such as monochlor-naphthalene, are quite suitable compounds for use in removing the carbon from engine cylinders, inasmuch as such compounds have a lubricating value in addition to their other properties, so that after use of the carbon remover the danger of the pistons binding because of solution of the lubricating oil on the cylinder wall is minimized. We have found a composition containing an admixture of a chlorinated naphthalene such as monochlor-naphthalene with a chlorinated benzene such as phenyl chloride gives very satisfactory results. Where a mixture of one halogenated hydrocarbon, such as a chlorinated naphthalene, with another halogenated hydrocarbon of different characteristics, such as phenyl chloride, is used in suitable proportions, superior solvent action upon the resistant binder is obtained over that produced by either solvent separately, or the additive effects of the two solvents when used separately.

In order to insure easy starting of an internal combustion engine after application of the carbon remover, a quantity of a highly volatile combustible may be incorporated in the composition. For example, high test gasoline functions very satisfactorily for this purpose.

As an example of a composition incorporating monochlor-naphthalene and phenyl chloride as well as high test gasoline, which has

given quite satisfactory results, the following is mentioned:

	Per cent by volume
Halowax oil (monochlor-naphthalene)	20
5 Phenyl chloride	20
Benzol	20
Denatured ethyl alcohol	20
High test gasoline	20

- 10 In the above example using equal proportions of the two chlorinated aromatic hydrocarbons of different characteristics a superior solvent action is obtained. Where the other constituents are maintained in the same proportion, one of the chlorinated aromatic hydrocarbons may be somewhat increased in proportion as the other chlorinated aromatic hydrocarbon is correspondingly decreased with good results; or where the combined proportions of the other constituents are altered, the combined proportions of the two chlorinated hydrocarbons may be altered while maintaining approximately the same ratios of these two constituents with good results.
- 15 In using the composition of this invention to remove carbon deposits from an internal combustion engine, the engine is first run until it is quite hot. Then the carbon remover is introduced into the cylinder, either by pouring through the spark plug opening or by drawing it into the cylinder through the intake manifold, care being taken to prevent escape of the solvent through the exhaust ports. Generally about 20 to 50 c. c. are added per cylinder. The motor is then allowed to stand for some time, preferably about six hours or over night, during which time the composition acts upon the binder and loosens the insoluble carbon and road dust free. The motor is then started and allowed to run a short time, the blast serving to blow the loosened material out through the exhaust.

Reference is herein made to our co-pending application, Serial No. 301,702, filed August 23, 1928, which discloses and claims a carbon remover composition containing in conjunction with a highly effective solvent ingredient, a sufficient quantity of a high boiling heat resisting material to maintain loosened carbon deposits in a moist condition. In the present case, there is disclosed and claimed such a carbon removing composition containing a high boiling heat resisting ingredient which has the double function of being an effective solvent for the deposits, and of maintaining the loosened deposits in a moist condition.

While the compositions herein described constitute preferred embodiments of the invention, it is to be understood that the invention is not limited to these precise compositions and that changes may be made therein without departing from the scope of the invention which is defined in the appended claims.

What is claimed is:

1. A composition for removing carbon deposits from engine cylinders comprising a solution of a chlorinated naphthalene in ethyl alcohol and benzol. 70
2. A composition for removing carbon deposits from engine cylinders comprising a mixture containing a halogenated naphthalene and a halogenated benzene giving a superior solvent action therewith. 75
3. A composition for removing carbon deposits from engine cylinders comprising a chlorinated naphthalene and a chlorinated benzene. 80
4. A composition for removing carbon deposits from engine cylinders comprising a chlorinated naphthalene, a chlorinated benzene, benzol and ethyl alcohol. 85
5. A composition for removing carbon deposits from engine cylinders comprising monochlor-naphthalene, phenyl chloride, benzol, ethyl alcohol and gasoline. 90
6. A composition for removing carbon deposits from engine cylinders, comprising a mixture containing an organic solvent which dissolves lubricating oil, and a proportion of a halogenated aromatic hydrocarbon sufficient to effectively soften carbon deposits. 95
7. A composition for removing carbon deposits from engine cylinders, comprising a mixture containing as essential ingredients halowax oil and another halogenated hydrocarbon in proportions sufficient to effectively soften the carbon deposits. 100
8. A carbon removing composition comprising a halogenated aromatic hydrocarbon. 105
9. A carbon removing composition comprising as an essential ingredient a chlorinated naphthalene. 110
10. A carbon removing composition comprising as an essential ingredient a chlorinated benzene. 115

In testimony whereof we hereto affix our signatures.

CHARLES A. THOMAS. 110
